UNITED STATES PATENT OFFICE.

JAMES T. COWLEY, OF SYRACUSE, NEW YORK, ASSIGNOR TO THE LAMSON COMPANY, OF SYRACUSE, NEW YORK, A CORPORATION OF MASSACHUSETTS.

POWER-CONTROL DEVICE FOR PNEUMATIC-DISPATCH SYSTEMS.

Application filed March 4, 1926. Serial No. 92,182.

This invention pertains to pneumatic dispatch systems of the so-called "minimum flow" vacuum type and relates more particularly to automatic power controlling apparatus for use in such a system.

Power control apparatus of this general character is disclosed in the patent to Libby No. 968,576, dated August 30, 1910. The patented apparatus provides automatic pressure actuated means for initiating a carrier impelling air flow through the transmission tube whenever a carrier is entered therein as well as means for cutting off such flow after the lapse of a predetermined period of time. While I regard the patented device as generally correct in principle and highly effective in practice I believe it preferable to have the cessation of carrier impelling air flow depend directly upon the discharge of the carrier from the delivery end of the tube rather than upon the operation of a timing device, and the principal object of this invention is to provide an improved power control apparatus comprising means actuatable automatically upon insertion of a carrier within the dispatch terminal to initiate flow of the air propelling current and also operating automatically when the last carrier emerges from the delivery terminal to cut off the air current without appreciable delay.

In the accompanying drawings I have disclosed one preferred embodiment of the invention by way of example;

Fig. 1 being a fragmentary elevation illustrating part of the central station desk of a pneumatic dispatch system having the improved power control apparatus applied thereto;

Fig. 2 is a vertical section to larger scale than Fig. 1 and taken on the line 2—2 of Fig. 5, showing the interior construction of the improved control apparatus, the several parts being in a position which they assume when the line is empty;

Fig. 3 is a view similar to Fig. 2 but showing the control valve open to permit carrier impelling air flow to pass through the transmission tube;

Fig. 4 is a view similar to Fig. 2 but showing the parts in the position which they occupy at the instant after the last carrier has been delivered from the transmission tube;

Fig. 5 is a horizontal section substantially on the line 5—5 of Fig. 4;

Fig. 6 is a fragmentary side elevation looking toward the left-hand side of the apparatus illustrated in Fig. 2;

Fig. 7 is a plan view of a cut-off device auxiliary to the control valve;

Fig. 8 is a fragmentary section to large scale substantially on the line 8—8 of Fig. 3; and

Fig. 9 is a fragmentary section substantially on the line 9—9 of Fig. 2.

Referring to the drawings, the numeral 1 indicates a fragmentary portion of the central station desk of a pneumatic dispatch system comprising transmission tubes, such for example as the tube 2 which leads from the central station desk. Each tube 2 is furnished with a delivery terminal 3 and is provided with a continuation 4 connecting it to an individual power control device indicated generally by the numeral 5. This power control device is connected in turn by means of a suction tube 7 to a vacuum drum or header 9 in which a low pressure is continually maintained by means of a suitable pump, exhaust or equivalent apparatus, not shown.

An open ended dispatch terminal 6 is provided at the central station for each of the transmission tubes 2, such dispatch terminal forming the entrance to that run of the tube which leads to the corresponding remote sending station. The above arrangement in general is old and well known in this art and further details of such general arrangement are therefore unnecessary, the present invention being confined to improvements in the power control apparatus per se.

Referring more particularly to Figs. 2 to 9 inclusive, the power control device proper comprises the hollow casing 8 provided at its upper end with a cover 8^a and at its lower end with a bottom member 8^b. The cover member 8^a is furnished with an opening, preferably defined by an annular flange 4^a, adapted to receive the lower end of the tube extension 4. The cover 8^a as here shown is separate from the body portion of the casing and is attached thereto in any desired manner, although if preferred the cover member may be integral with the body of the casing.

The bottom member 8^b is attached to the body of the casing by means of bolts 11 and the margin of a flexible diaphragm 12 is clamped between the body of the casing and the edge of the cover member 8^b. The space

13 between the diaphragm 12 and the bottom member 8^b communicates with the outer atmosphere by means of a small port 14 which is always open. The space 13 may also communicate with the outer atmosphere by means of a relatively large opening 15 provided with a flap-valve 16 which is normally held closed by means of a light spring 17. The space within the casing is divided 10 into an inlet chamber 18 and an outlet chamber 19 by means of a septum or partition 20. The space 18 communicates freely at all times with the transmission tube while the outlet chamber 19 freely communicates with 15 the suction tube 7 leading to the drum 9, the body portion 8 of the casing being furnished with a socket 22 for the reception of the end of the tube 7.

The partition or septum 20 is preferably 20 of U-shape and its upper wall 20^a is furnished with a valve aperture 21 which is preferably, though not necessarily co-axial with the tube extension 4. A controlling valve governs the passage of air through the 25 valve aperture 21. The controlling valve structure preferably comprises a disk-like head or valve proper 23 adapted to fit snugly within the aperture 21 and a body portion 24 which carries a second head or disk 25 30 at its lower end. This lower head 25 has a free sliding fit in a cylindrical chamber 25 provided in the lower wall 20^b of the septum 20. The chamber 25 is closed on all sides but communicates by means of a passage 35 26 extending through the body 24 of the valve with the space above the valve member 23. The pressure upon the upper and lower 40 faces of the valve structure is thus always balanced so that the valve may move very easily under all conditions.

The valve body 24 is secured to the upper 45 end of a valve stem 27 sliding in a guide opening in a boss 28 on the lower wall 20^b of the septum 20. The stem 27 also passes through a guide opening in a boss 31 upon the bottom member 8^b of the casing.

The valve stem is connected by a pin 29 to a clamping member 30 secured to the central part of the diaphragm 12. The lower 50 portion of the stem 27 is screw threaded as shown at 32 and receives an adjustable stop 33 adapted to engage the boss 31 as the valve stem moves upwardly, and thus to limit such upward movement. A spring 34 surrounds the outwardly projecting part of the valve stem, bearing at one end against the under surface of the member 8^b of the case and at its other end against an abutment member 35 which may be adjusted to 55 vary the tension of the spring by means of a nut 36 engaging the threaded portion of the stem.

When the valve 23 is closed a minimum 60 flow of air through the transmission tube toward the suction drum is provided for by

means of passage 37 extending from the chamber 18 to the chamber 19 and which is controlled by a rotary valve plug 38. By adjustment of this plug the amount of air flowing through the passage 37 may be regulated. While this mode of providing for the minimum flow is preferred, since it permits adjustment of the flow from a point outside of the casing, I contemplate that this minimum flow may be provided for in 75 any of the ways usual to apparatus of this type, as for example by holding the controlling valve slightly spaced from its seat when closed.

A lever arm 39 is mounted in the upper 80 part in the inlet chamber 19 and supports an auxiliary valve or cut-off device, 40, here shown as a shallow inverted circular cup-like cover having a depending annular flange rim 41. The flat upper surface of the member 40 is of substantial area and is preferably disposed directly in the path of the air entering the inlet chamber 18 from the tube extension 4. To hold the auxiliary valve or cut-off device in its normal inoperative position as indicated in Fig. 2, I provide a spring 42 secured at one end to the lever arm 39 and at the other to a rod 43 passing up through an opening in the cover 8^a, the upper end of the rod being screw threaded 85 for engagement by an adjusting nut 43 by means of which the tension of the spring 42 may be varied. A bracket 44 projects from the inner surface of the cover 8^a and acts as a stop to limit upward movement of the 90 cut-off device 40.

The cup-like auxiliary valve or cut-off device 40 is of an internal diameter somewhat greater than the valve member 23 and the flange 41 is of such a depth that when the cut-off device is positioned as shown in Fig. 4, the valve 23 being fully open, the cut-off device completely houses the valve 23 while the lower edge of its rim 41 rests against the septum 20 and thus forms a 105 complete closure for the valve aperture 21. When in this position the flange 41 of the cut-off device also constitutes a closure for the entrance end of the minimum flow passage 37.

Referring more especially to Figs. 7 and 8, the lever arm 39 is preferably provided at its end with spaced ears 45 and 46 having aligned journal openings for the reception of the aligned pintle members 47 and 48 110 respectively projecting inwardly from the wall of the casing 8.

Preferably the side wall of the casing 8 is furnished with an aperture 47 leading to the outer atmosphere and this aperture is 115 normally closed by a flap-valve 48. A pivoted arm 49 is arranged within the inlet chamber 18 with its free end disposed in position to engage the inner surface of the valve member 48. The upper end of this 120

5 arm 49 is provided with a journal opening for the reception of a pivot member 51 (Fig. 8) whose opposite ends are received within the inner portions of the journal openings in 10 the ears 45 and 46 respectively of the lever 39. The arm 49 is thus pivotally supported between the ears 45 and 46 and is adapted to be actuated by a finger 52 projecting downwardly from the arm 39.

10 The operation of the device is substantially as follows, it being assumed that when the transmission tube is empty the controller parts occupy the positions shown in Fig. 2 and that a suitable vacuum or sub-atmospheric pressure is maintained in the suction tube 7 by an exhauster or other suitable device. Under these conditions a small or minimum flow of air is entering the open terminal 6 and after passing through the 15 tubes 2 and 4, traverses the upper part of the inlet chamber 18 of the casing and passes on through the passage 37 to the suction tube 7. The spring 34 is so adjusted that the slight decrease in pressure in the chamber 18 occasioned by this minimum flow is 20 not sufficient to raise the diaphragm 12.

When a carrier is inserted in the transmission tube either at the terminal 6 or at the outlying sub-station, the minimum flow 25 is cut-off or substantially diminished, thus resulting in a decrease in pressure in the inlet chamber 18. As the diaphragm 12 is always exposed to the pressure in the chamber 18, such pressure being substantially 30 that of the transmission tube, and as the opposite side of the diaphragm is exposed through the small opening 14 to atmospheric pressure, the diaphragm now rises in opposition to the spring 34 and opens the control valve 23. The valve orifice 14 is made quite 35 small so that the rise of the diaphragm will be gradual, thus avoiding the production of heavy oscillations in the air current which is established by the opening of the valve 23.

40 As soon as the valve 23 is opened, a full carrier impelling air flow is set up in the transmission tube, the air current passing through the latter into the chamber 18 and thence through the valve orifice 21 into the chamber 19 and tube 7. The spring 42 is so 45 adjusted that although the broad upper surface of the member 40 is subjected to this carrier impelling air flow, it is maintained in the position shown in Fig. 2, until the last carrier emerges from the transmission tube.

When the last carrier is delivered from the transmission tube a sudden rush of air 50 ensues, the velocity of the air during such sudden rush exceeding the velocity of the carrier impelling air current. The impact of this sudden rush of air upon the broad upper surface of the member 40 overcomes the tension of spring 42 and the latter yields, 55 permitting the member 40 to swing down in-

to the position shown in Fig. 4. The pivotal axis of the lever 39 is so disposed that the cup-like cut-off member 40 swings freely down over the opened valve 23 without contact with the latter until as above stated it 60 occupies the position shown in Fig. 4 where the lower edge of its flange 41 engages the upper wall of the septum 20 in substantially concentric relation to the edge of the opening 21.

While the cut-off member initially responds to the sudden rush of air, thus moving toward the position of Fig. 4, it is assisted in completing its movement by the increasingly different pressures upon its upper 65 and lower surfaces as it approaches the cutting-off position, since as soon as its lower edge passes the valve member 23 it begins to restrict the air passage beneath the edge of the valve 23 and thus to cut off the flow to 70 some extent, so that during the final part of its movement it is positively sucked down to its seat. Thus even though the rush of air may be but momentary, the cut-off device is 75 caused to assume the cutting-off position 80 with certainty.

As the cut-off device reaches the position of Fig. 4, its flange 41 closes the entrance to the minimum flow passage 37 so that the inlet chamber 18 is completely cut off from the 85 suction tube. The air pressure upon the upper and lower surfaces of the valve structure is now instantaneously balanced through the passage 27 and since the pressure in the chamber 18 rises substantially to that of the atmosphere as soon as the cut-off member is seated, the spring 34 is now free to return the valve 23 to its closed position. This 90 movement may take place rapidly, since the flap valve 16 opens outwardly very easily to 95 permit the air trapped in the chamber 18 to escape.

In order to make sure that the air pressure in chamber 18 is restored substantially 100 to that of the atmosphere immediately upon closure of the cut-off member, the valve 48 is provided, and as the lever 39 swings down 105 into the position of Fig. 4 the finger 52 engages the lever 49 and opens the valve 48, thus permitting atmospheric air to enter the chamber 18 freely without passing through the length of the transmission tube, and compensating any suction leakage past the controlling valve or through the minimum flow 110 passage.

With the parts arranged as herein disclosed, the diaphragm 12 being substantially concentric with the tube extension 4, there is quite a pronounced hammer effect from the moving column of air directly upon closure of the cut-off member 40. This hammer blow of the air column acts upon the upper surface of the diaphragm 12 and assists the spring 34 in closing the valve 23. While this 115 hammer effect is useful in quickening the 120

closure of the control valve, it is not necessary to the operation of the device and if desired the diaphragm 12 may be arranged in some position such that it does not receive the direct impact of the hammer blow of the air column.

From the above description it will be noted that while the valve 23 with its actuating diaphragm 12 determines the establishment of carrier impelling air flow through the transmission tube, the cut-off device 40, acting independently of the valve 23, determines the termination of such carrier impelling flow.

While certain specific structural features have herein been described as desirable in embodying the present invention in an operative device, I contemplate that various changes in the shape, proportion and arrangement of parts may be made without departing from the spirit of the invention.

Moreover, while the apparatus has been shown as embodied in a suction system, it is contemplated that certain of its broader features might well be applicable to a pressure minimum flow system, and further that under certain circumstances, certain of its operative parts might be dispensed with or united in a single member having their combined function.

I claim:

1. Power control apparatus for a pneumatic dispatch system of the minimum flow type having a transmission tube, said apparatus comprising a pair of independent controlling devices for cutting off carrier impelling air flow through the transmission tube, one of said devices normally being so disposed as to cut off carrier impelling air flow, but opening in response to the introduction of a single carrier into the transmission tube, and the other of said devices normally being open but closing in response to delivery of the last carrier from the tube.

2. Power control apparatus for a pneumatic dispatch system of the minimum flow type having a transmission tube, said apparatus comprising a pair of independent controlling devices for cutting off carrier impelling air flow through the transmission tube, one of said devices normally being closed, and a pneumatic responsive to pressure change resulting from reduction in the minimum flow through the transmission tube and by such response opening said normally closed device to permit a carrier impelling flow through the tube, the other of said controlling devices normally being open but closing to cut off carrier impelling air flow through the tube upon delivery of the last carrier from the latter.

3. Power control apparatus for a pneumatic dispatch system of the minimum flow type having a transmission tube, said apparatus comprising a pair of independent controlling devices for cutting off carrier impelling air flow through the transmission tube, one of said devices normally being closed, and a pneumatic responsive to pressure change resulting from reduction in the minimum flow through the transmission tube and by such response opening said normally closed device to permit a carrier impelling flow through the tube, the other of said controlling devices normally being open but closing to cut off carrier impelling air flow through the tube upon delivery of the last carrier from the latter.

trolling devices for cutting off carrier impelling air flow through the transmission tube, one of said devices normally being closed, and a pneumatic connected to the normally closed controlling device, the pneumatic being exposed to transmission tube pressure and responding to reduction in such pressure due to reduction of the minimum flow by introduction of a carrier into the transmission tube and by such response opening said normally closed controlling device to permit a carrier impelling air flow through the transmission tube, the second of said controlling devices normally being open and being at all times exposed to transmission tube pressure, said device responding to the rush of air incident to delivery of a carrier from the tube to close and thereby cut off carrier impelling air flow.

4. Power control apparatus for a pneumatic dispatch system of the minimum flow type having a transmission tube, said apparatus comprising a pair of independent controlling devices for cutting off carrier impelling air flow through the transmission tube, one of said devices normally being closed, and the other of said devices normally being open, both of said devices being exposed at all times to transmission tube pressure, the normally closed device opening when a carrier is introduced into the transmission tube and the normally open device closing when a carrier is delivered from the tube.

5. Power control apparatus for a pneumatic dispatch system of the minimum flow type having a transmission tube, said apparatus comprising a pair of independent valve devices for cutting off carrier impelling air flow through the transmission tube, one of said devices normally being positioned to cut off carrier impelling air flow and the other normally being open, and means for opening the normally closed device when a carrier is inserted in the transmission tube, the normally open device being always exposed to transmission tube pressure and moving to closed position in direct response to the sudden rush of air when a carrier leaves the tube.

6. Power control apparatus for a pneumatic dispatch system of the minimum flow type having a transmission tube, said apparatus comprising a pair of independent valve devices for cutting off carrier impelling air flow through the transmission tube, one of said devices normally being closed and the other normally being open, and a pneumatic for opening the normally closed device when a carrier is inserted in the transmission tube, the normally open device having a broad surface always exposed to the air current flowing through the transmission tube and responding to air flowing through the transmission tube at a velocity

in excess of that of carrier impelling flow and by such response causing said device to close.

7. Power control apparatus for a pneumatic dispatch system of the minimum flow type having a transmission tube, said apparatus comprising a pair of independent controlling devices for cutting off carrier impelling air flow through the transmission tube, one of said devices normally being closed and the other open, and a pneumatic for opening the normally closed controlling device when a carrier is inserted in the transmission tube, the normally open device comprising a pivotally supported element exposing a surface of substantial area to the carrier impelling air current, and yielding means normally holding said device open in opposition to the pressure of the air current against said surface but permitting the device to close when the velocity of the air current exceeds the normal velocity of carrier impelling flow.

8. Power control apparatus for a pneumatic despatch system of the minimum flow type having a transmission tube, said apparatus comprising a pair of independent controlling devices for cutting off carrier impelling air flow through the transmission tube, one of said devices normally being closed and the other open, means for automatically opening the normally closed device to establish carrier impelling air flow when a carrier is inserted in the tube, the normally open device comprising a pivotally supported member having a broad surface disposed transversely of the air current, a spring for yieldably holding said surface in normal position in opposition to the pressure of carrier impelling air flow, and means for adjusting the spring so that the device may move in response to a velocity of air flow exceeding that of normal carrier impelling and thereby close to cut off the flow.

45 9. Power control apparatus for a pneumatic dispatch system having a transmission tube means for creating carrier impelling air flow through the tube, a controlling valve governing carrier impelling flow of air through the transmission tube, a minimum flow of air through the tube normally being permitted when said valve is closed, and a pneumatic responsive to a change in pressure due to introduction of a carrier into the transmission tube and by such response opening the controlling valve, one side of the pneumatic being at all times exposed to transmission tube pressure, said apparatus comprising means disposed at the inlet side of the controlling valve for cutting off the carrier impelling air flow when the carrier is delivered from the transmission tube.

10. Power control apparatus of the minimum flow type for a pneumatic dispatch system having a transmission tube, means for

creating carrier impelling air flow through the tube, a controlling valve governing carrier impelling flow of air through the transmission tube, a minimum flow of air through the tube normally being permitted when said valve is closed, and a pneumatic responsive to a change in pressure due to introduction of a carrier into the transmission tube and by such response opening the controlling valve, said apparatus comprising means responsive to the rush of air through the tube incident to delivery of a carrier from the latter and by its response cutting off carrier impelling air flow through the tube, said cut-off means being disposed at the inlet side 80 of the valve and being movable to closed position without changing the position of the controlling valve.

11. Power control apparatus for a pneumatic dispatch system having a transmission tube, means for creating carrier impelling air flow through the tube, a controlling valve governing carrier impelling flow of air through the transmission tube, a minimum flow of air through the tube normally being 85 permitted when the valve is closed, and a pneumatic responsive to a change in pressure due to introduction of a carrier into the transmission tube and by such response opening the controlling valve, said apparatus comprising a pivoted cut-off device at the inlet side of the valve, said cut-off device responding to the rush of air incident to delivery of a carrier from the tube to cut-off said flow independently of any action of the 90 main valve.

12. Power control apparatus for a pneumatic dispatch system of the minimum flow type having a transmission tube, and means for creating carrier impelling air flow therethrough, said apparatus being provided with chambers communicating respectively with the transmission tube and flow creating means, a septum separating said chambers, the septum having a valve aperture therethrough, said aperture being open during the flight of a carrier through the tube and means directly responsive to the sudden rush of air incident to delivery of the carrier from the tube for closing said valve aperture.

13. Power control apparatus for a pneumatic dispatch system having a transmission tube, means for creating carrier impelling air flow therethrough, a casing provided with chambers communicating respectively with the transmission tube and flow creating means, a septum separating said chambers, the septum having a valve aperture therethrough, a controlling valve for closing said aperture to terminate carrier impelling air flow through said tube, a minimum flow of air through the tube normally being permitted when the controlling valve is in closed position, and a pneumatic responsive 130

- to pressure change resulting from introduction of a carrier into the tube and by such response opening the controlling valve, said apparatus comprising a cup-like cover adapted to close the valve aperture independently of the controlling valve, said cover moving to aperture-closing position when the carrier is delivered from the transmission tube.
- 10 14. Power control apparatus for a pneumatic dispatch system of the minimum flow type having a transmission tube, and means for creating carrier impelling air flow therethrough, said apparatus being provided with chambers communicating respectively with the transmission tube and flow creating means, a valve aperture providing communication between said chambers, a pivoted cover adapted to close the valve aperture, and
- 15 yielding means normally holding the cover in inoperative position during the flight of a carrier through the tube, the cover closing the valve aperture in response to the rush of air following delivery of the carrier from the tube.
- 20 15. Power control apparatus for a pneumatic dispatch system having a transmission tube, means for creating carrier impelling air flow therethrough, means providing chambers communicating respectively with the transmission tube and flow creating means, a septum separating said chambers, the septum having a valve aperture therethrough, a controlling valve for closing said
- 25 aperture to terminate carrier impelling air flow through said tube, a minimum flow of air through the tube normally being permitted when the controlling valve is in closed position, and a pneumatic responsive to pressure change resulting from introduction of a carrier into the tube and by such response opening the controlling valve, said apparatus comprising a cover adapted to close the valve aperture independently of the controlling valve, said cover normally standing in the path of the air current flowing toward the aperture and moving to aperture closing position in response to the rush of air incident to delivery of the carrier from the tube.
- 30 16. Power control apparatus for a pneumatic dispatch system of the minimum flow type having a transmission tube and means for creating carrier impelling air flow therethrough, said apparatus being provided with chambers communicating respectively with the transmission tube and flow creating means, a valve aperture connecting said chambers, a pivoted cover for the valve aperture normally standing in open inoperative position and presenting an inclined face to the air current flowing toward the aperture, and yieldable means normally holding the cover in said inoperative position, the cover swinging in response to the sudden

rush of air which occurs when the carrier leaves the tube and thereby cutting off carrier propelling air flow through the tube.

17. Power control apparatus for a pneumatic dispatch system having a transmission tube and means for creating carrier impelling air flow therethrough, said apparatus being provided with chambers communicating respectively with the transmission tube and flow creating means, there being a valve aperture providing communication between said chambers, a controlling valve for closing said aperture to terminate carrier impelling air flow through said tube, the apparatus having a minimum flow passage leading from the inlet chamber, a pneumatic responsive to pressure change resulting from introduction of a carrier into the tube and by such response opening the controlling valve, and a cover normally occupying an inoperative position spaced from the valve aperture, said cover moving in response to the sudden rush of air through the tube incident to delivery of a carrier from the latter to an operative position in which it closes the valve aperture in the septum independently of the controlling valve, the cover having a flange which closes the minimum flow passage when the cover is in said operative position.

18. Power control apparatus for a pneumatic dispatch system having a transmission tube and means for creating carrier impelling air flow therethrough, said apparatus being provided with chambers communicating respectively with the transmission tube and flow creating means, a septum separating said chambers, the septum having a valve aperture therethrough, a controlling valve for closing said aperture to terminate carrier impelling air flow through said tube, the apparatus having a passage leading from the inlet chamber at a point adjacent to the septum to provide for a minimum flow of air through the tube when the controlling valve is in closed position, a pneumatic responsive to pressure change resulting from introduction of a carrier into the tube and by such response opening the controlling valve, and a cover of inverted cup-like shape having a depending circular rim, the lower edge of the rim being normally spaced from the septum, said cover moving in response to the rush of the air when a carrier leaves the tube until the edge of the rim is concentric with the valve aperture and engages the septum thereby cutting off the flow of air through the valve aperture, the rim at the same time forming a closure for the entrance to the minimum flow passage.

19. Power control apparatus for a pneumatic dispatch system having a transmission tube and means for creating carrier impelling air flow therethrough, said apparatus being provided with chambers communicat-

ing respectively with the transmission tube and flow creating means, a septum separating said chambers, the septum having a valve aperture therethrough, a controlling valve for closing said aperture to terminate carrier impelling air flow through said tube, a minimum flow of air through the tube normally being permitted when the controlling valve is in closed position, a pneumatic responsive to pressure change resulting from introduction of a carrier into the tube and by such response opening the controlling valve, a substantially circular movable cover normally spaced from the septum, and means movably supporting the cover to permit it to move in response to the sudden rush of air through the tube when the carrier leaves the latter into a position where its edge is coaxial with and bears against the septum at the margin of the aperture in the latter thereby cutting off carrier impelling air flow.

20. Power control apparatus for a pneumatic dispatch system having a transmission tube and means for creating carrier impelling air flow therethrough, said apparatus being provided with chambers communicating respectively with the transmission tube and flow creating means, the chambers communicating by means of a valve aperture, a controlling valve for closing said aperture to terminate carrier impelling air flow through said tube, a minimum flow of air through the tube normally being permitted when the controlling valve is in closed position, a pneumatic responsive to pressure change resulting from introduction of a carrier into the tube and by such response opening the controlling valve, the controlling valve in opening moving oppositely to the air current, and a cupped cover normally spaced from the valve aperture so as to permit free air flow through the latter, said cover moving in response to the rush of air in the tube incident to delivery of a carrier therefrom until it houses the open valve and cuts off the air flow through the aperture.

21. Power control apparatus for a pneumatic dispatch system having a transmission tube, means for creating carrier impelling air flow therethrough, a casing provided with chambers communicating respectively with the transmission tube and flow creating means, a septum separating said chambers, the septum having a valve aperture therethrough, a controlling valve for closing said aperture to terminate carrier impelling air flow through said tube, a minimum flow of air through the tube normally being permitted when the controlling valve is in closed position, and a pneumatic responsive to pressure change resulting from introduction of a carrier into the tube and by such response opening the controlling valve, said apparatus comprising a movable cover dis-

posed in that chamber of the apparatus which communicates with the transmission tube, and a spring normally holding the cover in inoperative position, the spring yielding to permit the cover to move to a position where it covers the aperture in the septum when a carrier is delivered from the tube.

22. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted when the controlling valve is closed, and a pneumatic constantly exposed on one side to the pressure in the inlet chamber, said pneumatic being connected to the valve and automatically opening the latter when a carrier is inserted in the transmission tube, said apparatus comprising means independent of the controlling valve for cutting off communication between the inlet and outlet chambers and for substantially terminating the minimum flow when the carrier is delivered from the transmission tube.

23. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted when the controlling valve is closed, and a pneumatic constantly exposed on one side to the pressure in the inlet chamber, said pneumatic being connected to the valve and automatically opening the latter when a carrier is inserted in the transmission tube, said apparatus comprising an air operated cut-off device independent of the controlling valve for cutting off communication between the inlet and outlet chambers, a spring normally holding the cut-off device in inoperative position, and means for adjusting the tension of the spring, the cut-off device moving from inoperative to operative position in response to the rush of air following delivery of the carrier from the tube, said cut-off device when in operative position also substantially cutting off the minimum flow.

24. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally be-

- ing permitted when the valve is closed, and a pneumatic constantly exposed on one side to the pressure in the inlet chamber, said pneumatic being connected to the valve and 5 automatically opening the latter when a carrier is inserted in the transmission tube, said apparatus comprising a movable cut-off device yieldably supported directly in the path of air through the inlet chamber, the cut-off 10 device being moved by air having a velocity exceeding that of normal carrier impelling air flow and by such movement cutting off communication between the inlet and outlet chambers and simultaneously cutting off the 15 minimum flow.
25. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted when the controlling valve is in closed position, and a pneumatic constantly exposed on one side to the pressure in the inlet chamber, said pneumatic being connected to the valve and automatically opening the latter when a carrier is inserted in the transmission tube, said apparatus comprising means independent of the controlling valve for simultaneously cutting-off carrier impelling air flow through the tube and for opening direct communication between the inlet chamber and the outer atmosphere. 90
28. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted when the controlling valve is in closed position, and a pneumatic constantly exposed on one side to the pressure in the inlet chamber, said pneumatic being connected to the valve and automatically opening the latter when a carrier is inserted in the transmission tube, 95
- 35 to delivery of the carrier from the tube and thereby cutting off communication between the inlet and outlet chambers, and means actuatable by the cut-off device for opening communication between the inlet chamber and the outer atmosphere. 100
40. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted, when the controlling valve is in closed position, and a pneumatic constantly exposed on one side to the pressure in the inlet chamber, said pneumatic being connected to the valve and automatically opening the latter when a carrier is inserted in the transmission tube, 105
- 45 said apparatus comprising an air operated cut-off device within the inlet chamber, said device being independent of the controlling valve, said cut-off device moving in response to delivery of the carrier from the tube and thereby cutting off communication between the inlet and outlet chambers, and means actuatable by the cut-off device for opening communication between the inlet chamber and the outer atmosphere. 110
50. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air from the inlet chamber to the outlet chamber normally being permitted when the controlling valve is in closed position, and a pneumatic constantly exposed on one side to the pressure in the inlet chamber, said pneumatic being connected to the valve and automatically opening the latter when a carrier is inserted in the transmission tube, 115
- 55 said apparatus comprising a two armed lever pivotally supported within the inlet chamber, a cut-off member mounted upon one arm of the lever, said cut-off member when in operative position cutting off communication between the inlet and outlet chambers, a spring connected to the lever normally holding the cut-off device in inoperative position, and a normally closed valve controlling a passage connecting the inlet chamber directly with the 120
- 60 outer atmosphere, said valve being disposed in the path of movement of the other arm of the lever to be opened thereby when the cut-off device moves to operation. 125
65. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted when the controlling valve is in closed position, and a pneumatic constantly exposed on one side to the pressure in the inlet chamber, said pneumatic being connected to the valve and automatically opening the latter when a carrier is inserted in the transmission tube, said apparatus comprising an air operated device independent of the controlling valve for substantially completely cutting off communication between the inlet and outlet chambers. 130

30. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, there being a passage providing for a minimum flow of air from the inlet chamber toward the exhauster when the controlling valve is closed, and a pneumatic constantly exposed on one side to the pressure in the inlet chamber, said pneumatic being connected to the valve and automatically opening the latter when a carrier is inserted in the transmission tube, said apparatus comprising means movable independently of the controlling valve for cutting off communication between the inlet and outlet chambers, and for simultaneously closing the minimum flow passage, said last named means normally being inoperative but moving to operative position in response to the sudden rush of air through the system following the delivery of the carrier from the tube. 75
31. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, there being a passage leading from the inlet chamber to the outlet chamber to provide for a minimum flow of air when the controlling valve is in closed position, and a pneumatic constantly exposed on one side to the pressure in the inlet chamber, said pneumatic being connected to the valve and automatically opening the latter when a carrier is inserted in the transmission tube, said apparatus comprising means, independent of the controlling valve, located in the inlet chamber and responding to the rush of air following delivery of the carrier from the tube, to close the minimum flow passage and to cut off communication between the inlet and outlet chambers. 100
32. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted when the controlling valve is closed, and a pneumatic constantly exposed on one side to the pressure in the inlet chamber, said pneumatic being connected to the valve and automatically opening the latter when a carrier is inserted in the transmission tube, said apparatus comprising a hinged cover within the inlet chamber, a spring normally holding said cover in inoperative position, and adjustable means outside of the casing for so tensioning the spring that the cover moves to operative position in response to the rush of air through the system following delivery of the carrier from the tube and thereby cuts off communication between the inlet and outlet chambers. 125
33. Power control apparatus for a pneumatic dispatch system having a transmission tube, an exhauster, a casing provided with an inlet and an outlet chamber communicating respectively with the tube and exhauster, a controlling valve for governing carrier impelling air flow from the inlet to the outlet chamber, a minimum flow of air through the transmission tube normally being permitted when the controlling valve is closed, and a pneumatic constantly exposed on one side to the pressure in the inlet chamber, said pneumatic being connected to the valve and automatically opening the latter when a carrier is inserted in the transmission tube, the controlling valve moving into the inlet chamber when it opens, said apparatus comprising a cup-like cover within the inlet chamber, and means holding the cover in inoperative position during flight 95 of the carrier, but permitting it to move in response to the rush of air following delivery of the carrier from the tube until it houses the open valve and cuts off communication between the inlet and outlet chamber. 100
34. Power control apparatus for a pneumatic dispatch system of the vacuum minimum flow type having a transmission tube, an exhauster, a casing divided by a septum into an inlet and an outlet chamber communicating respectively with the transmission tube and the exhauster, the septum having an aperture, a controlling valve for closing the aperture, means tending to maintain the valve in closed position, a minimum flow of air through the transmission tube normally being permitted when the controlling valve is closed and a pneumatic for opening the valve, one side of the pneumatic being always exposed to transmission tube 110 pressure, the pneumatic responding to diminution in pressure in the tube due to the reduction of the minimum flow by insertion of a carrier in the tube and by its response opening the controlling valve, said apparatus comprising means independent of the controlling valve for cutting off both carrier impelling flow and minimum flow through the tube when the carrier is discharged from the latter. 115
35. Power control apparatus for a pneumatic dispatch system of the vacuum minimum flow type having a transmission tube, an exhauster, a casing divided by a septum into an inlet and an outlet chamber com- 120
- 130

municating respectively with the transmission tube and the exhauster, the septum having an aperture, and a controlling valve for closing the aperture, means tending to maintain the valve in closed position, a minimum flow of air through the transmission tube normally being permitted when the controlling valve is closed, said apparatus comprising a pneumatic for opening the valve, one side of the pneumatic being always exposed to transmission tube pressure, the casing having a space at the opposite side of the diaphragm which may communicate with the atmosphere through a port of large capacity, the pneumatic responding to diminution in pressure in the tube due to the reduction of the minimum flow by insertion of a carrier in the tube and by its response opening the controlling valve, the pneumatic being so arranged as to be freely exposed to the "hammer" effect which results from sudden stoppage of the column of air flowing through the system and in response to such hammer effect tending to close the controlling valve.

36. Power control apparatus for a pneumatic dispatch system of the vacuum minimum flow type having a transmission tube, an exhauster, a casing divided by a septum into an inlet and an outlet chamber communicating respectively with the transmission tube and the exhauster, the septum having an aperture, a controlling valve for closing the aperture, means tending to maintain the valve in closed position, a minimum flow of air through the transmission tube normally being permitted when the controlling valve is in closed position, a pneumatic for opening the valve, one side of the pneumatic being always exposed to transmission tube pressure, the pneumatic responding to diminution in pressure in the tube due to the reduction of the minimum flow by insertion of a carrier in the tube and by its response opening the controlling valve, said apparatus comprising means independent of the controlling valve for suddenly cutting off carrier impelling air flow when the carrier leaves the transmission tube, the pneumatic being so disposed as to experience substantially the full "hammer" effect of the suddenly arrested column of air in the system, thereby facilitating closure of the controlling valve.

37. Power control apparatus for a pneumatic dispatch system of the vacuum minimum flow type having a transmission tube, an exhauster, a casing divided by a septum into an inlet and an outlet chamber communicating respectively with the transmission tube and the exhauster, the septum having an aperture, a controlling valve for closing the aperture, and means tending to maintain the valve in closed position, a minimum flow of air through the transmission tube nor-

mally being permitted when the controlling valve is in closed position, said apparatus comprising a pneumatic for opening the valve, one side of the pneumatic being always exposed to transmission tube pressure, the pneumatic responding to diminution in pressure in the tube due to the reduction of the minimum flow by insertion of a carrier in the tube and by its response opening the controlling valve, the pneumatic constituting that wall of the inlet chamber which lies directly opposite to the point at which the air enters the latter, and a cut-off device disposed in the air current entering the inlet chamber and adapted to respond to air velocity above a predetermined amount to suddenly cut off carrier impelling air flow.

38. Power control apparatus for a pneumatic dispatch system of the vacuum minimum flow type having a transmission tube, an exhauster, a casing divided by a septum into an inlet and an outlet chamber communicating respectively with the transmission tube and the exhauster, the septum having an aperture, a controlling valve for closing the aperture, means tending to maintain the valve in closed position, a minimum flow of air through the transmission tube normally being permitted when the controlling valve is in closed position, a pneumatic for opening the valve, one side of the pneumatic being always exposed to transmission tube pressure, the pneumatic responding to diminution in pressure in the tube due to the reduction of the minimum flow by insertion of a carrier in the tube and by its response opening the controlling valve, and means for varying the minimum flow, said apparatus comprising a cut-off device disposed in the air current entering the inlet chamber and adapted to respond to air velocity exceeding a predetermined amount and by its response suddenly cutting off both the carrier impelling and minimum air.

39. Power control apparatus for a pneumatic dispatch system of the vacuum minimum flow type having a transmission tube and an exhauster, a casing divided by a septum into an inlet and an outlet chamber communicating respectively with the transmission tube and the exhauster, the septum having an aperture, a controlling valve for closing the aperture, means tending to maintain the valve in closed position, a minimum flow of air through the transmission tube normally being permitted when the controlling valve is in closed position, a pneumatic for opening the valve, one side of the pneumatic being always exposed to transmission tube pressure, the pneumatic responding to diminution in pressure in the tube due to the reduction of the minimum flow by insertion of a carrier in the tube and by its response opening the controlling valve, and means operative to cut off carrier impelling

air flow through the tube while the controlling valve is in open position.

40. Power control apparatus for a pneumatic dispatch system of the vacuum minimum flow type having a transmission tube, an exhauster, a casing divided by a septum into an inlet and an outlet chamber communicating respectively with the transmission tube and the exhauster, the septum having an aperture, a controlling valve for closing the aperture, means tending to maintain the valve in closed position, a minimum flow of air through the transmission tube normally being permitted when the controlling valve is closed, a pneumatic for opening the valve, one side of the pneumatic being always exposed to transmission tube pressure, the pneumatic responding to diminution in pressure in the tube due to the reduction of the minimum flow by insertion of a carrier in the tube and by its response opening the controlling valve, and means for adjustably limiting the opening movement of the controlling valve, said apparatus comprising a movable cut-off device disposed in the current of air on its way to the controlling valve, said device moving in response to a velocity of air flow exceeding that necessary to propel the carrier through the tube and by such response cutting off the air flow while the controlling valve is still in open position.

41. Power control apparatus for a pneumatic dispatch system of the vacuum minimum flow type having a transmission tube, an exhauster, a casing divided by a septum into an inlet and an outlet chamber communicating respectively with the transmission tube and the exhauster, the septum having an aperture, a controlling valve for closing the aperture, means tending to maintain the valve in closed position, a minimum flow of air through the transmission tube normally being permitted when the controlling valve is closed, and a pneumatic for opening the valve, one side of the pneumatic being always exposed to transmission tube pressure, the pneumatic responding to diminution in pressure in the tube due to the reduction of the minimum flow by insertion of a carrier in the tube and by its response opening the controlling valve, said apparatus comprising an air actuated check device independent of the controlling valve for cutting off air flow through the tube when the velocity of flow exceeds a predetermined amount.

42. Power control apparatus of the vacuum minimum flow type having a transmission tube, a suction tube, a casing divided into an inlet and an outlet chamber communicating respectively with the transmission tube and the suction tube, a controlling valve governing a passage leading from the inlet to the outlet chamber, means tending to maintain the valve in closed position,

minimum flow of air through the transmission tube normally being permitted when the controlling valve is in closed position, and a pneumatic for opening the controlling valve thereby substantially equalizing the pressure in the inlet chamber with that in the outlet chamber, the pneumatic responding to diminution in pressure in the tube due to reduction of the minimum flow by insertion of a carrier in the tube, and by such response opening the controlling valve, thereby exposing the pneumatic to the pressure of the outlet chamber, said apparatus comprising air actuated means responsive to increase in velocity in the air current beyond a predetermined amount for suddenly cutting off the pneumatic from the outlet chamber pressure.

43. Power control apparatus of the vacuum minimum flow type having a transmission tube and a suction tube, a casing divided into an inlet and an outlet chamber communicating respectively with the transmission tube and the suction tube, a controlling valve governing a passage leading from the inlet to the outlet chamber, means tending to maintain the valve in closed position, there being a passage leading from the inlet chamber to provide for a minimum flow of air through the transmission tube when said valve is in closed position, a pneumatic for opening the controlling valve, the pneumatic responding to diminution in pressure in the tube due to reduction of the minimum flow by insertion of a carrier in the tube and by such response opening the controlling valve, thereby exposing the pneumatic to a pressure substantially equaling that of the outlet chamber, and an air actuated cut-off device in the inlet chamber, said device normally being inoperative but moving in response to the rush of air following delivery of the carrier from the tube to an operative position in which it closed the passage from the inlet to the outlet chamber, said device having an element which closes the minimum flow passage when the device occupies said operative position.

44. Power control apparatus of the vacuum minimum flow type having a transmission tube and a suction tube, a casing divided into an inlet and an outlet chamber communicating respectively with the transmission tube and the suction tube, a controlling valve governing a passage leading from the inlet to the outlet chamber, means tending to maintain the valve in closed position, a minimum flow of air through the transmission tube normally being permitted when the controlling valve is closed, a pneumatic for opening the controlling valve, the pneumatic responding to diminution in pressure in the tube due to reduction of the minimum flow by insertion of a carrier in the tube and by such response opening the

controlling valve, thereby exposing the pneumatic to the pressure of the outlet chamber, means for maintaining a substantially balanced pressure upon opposite sides of the controlling valve, and a normally inoperative cut-off device located in the inlet chamber, said device comprising a part exposing a broad surface transversely to the air cur-

rent flowing through said chamber and moving in response to air velocity exceeding that of carrier propelling air flow to a position such that it closes said passage from the inlet chamber to the outlet chamber.

Signed by me at Syracuse New York this second day of March, 1926.

JAMES T. COWLEY.
